UNITED STATES PATENT OFFICE.

ROBERT K. CARPENTER, OF MEDFORD, MASSACHUSETTS.

HORSE-CLIPPING MACHINE.

SPECIFICATION forming part of Letters Patent No. 281,668, dated July 24, 1883.

Application filed May 23, 1883. (Model.)

To all whom it may concern:

Be it known that I, ROBERT K. CARPENTER, of Medford, in the county of Middlesex, State of Massachusetts, have invented a certain new and useful Improvement in Horse-Clipping Machines, of which the following is a description sufficiently full, clear, and exact to enable any person skilled in the art or science to which said invention appertains to make and use the same, reference being had to the accompanying drawings, forming a part of this specification, in which—

Figure 1 is a vertical longitudinal section of the handle and mechanism immediately connected therewith for operating the cutter, and a sectional view of the flexible shaft; Fig. 2, an end view of the same; Fig. 3, an isometrical perspective view of the clipper complete, and Fig. 4 a vertical longitudinal section of the flexible shaft.

Like letters of reference indicate corresponding parts in the different figures of the drawings.

My invention relates to that class of horse clippers or clipping machines which are designed to be operated by hand; and it consists in a novel construction and arrangement of the parts, as hereinafter more fully set forth and claimed, by which a more effective device of this character is produced than is now in ordinary use.

The nature and operation of the improvement will be readily understood by all conversant with such matters from the following explanation, its extreme simplicity rendering an elaborate description unnecessary.

In the drawings, A represents the pedestal, B the standard, and C the drive-wheel. The standard is rendered vertically adjustable in the pedestal by means of a screw, x, the drive-wheel being pivoted thereto at m and provided with the handle i.

Projecting laterally from the upper end of the standard there is a stud, v, and centrally pivoted thereto there is a bar, D, provided near its rear or outer end with the counterbalance or weight E, which is rendered adjustable thereon by the screw b.

A small wheel, G, is journaled on the shaft z in the upper part of the standard B, as shown

in Fig. 3, this wheel being connected by the belt H with the driving-wheel C.

Projecting downwardly from the forward end of the bar D there are two vertically-arranged bars, J, connected by the cross-bar m, 55 and provided with longitudinal slots h, these bars being rendered adjustable on the bar D by the screws f and thimbles g.

Journalized in the lower ends of the bars J, there is a rod, K, which is connected with the shaft z, on which the wheel G is journaled by means of a short flexible shaft, L. This shaft is composed of a double helix or coil of wire, x, inclosed in a rubber or leather covering, j, as best seen in Fig. 4, and is connected to the rod K and shaft z by means of the screws n. The rod K is hollow, and carries at its outer end a rod, M, which is fitted to slide therein and rendered adjustable by the screw p.

Attached to the outer end of the rod M there 70 is a short flexible shaft, N, constructed substantially in the same manner as the shaft L, and connected with the shaft N there is a rod, O, carrying a tube, P, the tube being provided with a short rod, Q, the rods O and Q being 75 fitted to slide in the tube, and rendered adjustable therein by means of the screws q.

Attached to the outer end of the rod Q there is a short flexible shaft, R, as best seen in Fig. 1, this shaft being connected with the rod S 80 in the interior of the cutter-head U by means of the screw r and screw-thimble t.

A cutter, T, of the usual construction is journaled in the head U, and connected to the inner end of the shaft S by means of a short 85 flexible shaft, W, this shaft being also constructed in substantially the same manner as the shaft L. A hole, d, is formed in the rear of the cutter-head, directly opposite the inner end of the shaft y, on which the cutter T is 90 journaled, this hole being designed to receive the screw-thimble t on the flexible shaft R, thereby enabling said shaft to be connected directly with the shaft y, if desired.

It will be obvious that the rods K M O Q, 95 tube P, and shafts N R form a continuous shaft, connecting the shaft z with the cutter-head U, this shaft being rendered extensible by the screws p q, and flexible, or adapted to be turned in either direction, by means of the shafts N R L. 100

It will also be obvious that the rods K M may be easily elevated or depressed, as desired, the bars J being loosely connected to the thimbles *g* by means of the screws *f*, and said 5 rods counterbalanced by the weight E.

The flexible shafts W, L, N, and R are each provided on their interiors with a chain, F, attached to the connecting-shafts in the usual manner to form a flexible joint, no special novelty being claimed for the mode of constructing the flexible shafts.

In clipping-machines of this character the cutter T is usually connected to the driving-shaft S by means of interposed miter-gears, 15 the rod K and shaft *z* being also connected in the same manner. These gears, however, are objectionable on account of the noise they produce in running the machine, which is liable to frighten the horse being clipped, and also 20 for the reason that the joint formed between the rod K and shaft *z* cannot be rendered sufficiently flexible when such gears are used. My invention is designed to obviate these objections, and to that end I make use of the flexible shaft W for connecting the shaft *y* and rod S in the head U, and also for connecting the rod K to the shaft *z*. I also use the shaft N to 25 form a flexible joint between the rods M O, and the shaft R to form a flexible connection between the rod Q and the cutter-head U, thereby adapting the pipe P to be swung around into parallelism with the rod K, and rendering the clipper much more effective in its operations than those of ordinary construction.

30 It is sometimes desirable to connect the rod Q directly with the shaft *y*, and this I accomplish by means of detaching the screw-thimble *t* from the screw *r*, removing the flexible shaft W from the cutter-head U, passing the thimble 35 through the hole *d* into the head, and screwing it onto the inner end of the shaft *y*, the opposite end of the shaft R being then connected by the screw-thimble *e* to the rod Q, thus leav-

ing the handle 20 projecting at right angles to the rod R, and rendering the clipper more convenient for use in performing some parts of the operation of clipping the horse.

It will be obvious that the rod K may be secured at any desired elevation by means of the screws *f*, these screws, when turned in firmly, preventing the bar D from swiveling on the pivot or stud *v*.

Having thus explained my invention, what I claim is—

1. In a horse-clipping machine, the cutter 55 T, connected with the rod S by means of the flexible shaft W, in combination with the cutter-head U and means for operating the cutter, substantially as described.

2. In a horse-clipping machine, the shaft *y*, 60 carrying the cutter T, and adapted to be connected directly with the flexible shaft R by means of the screw-thimble *t*, and also with the shaft S, substantially as set forth.

3. In a horse-clipping machine, the slotted 65 bars J, provided with the screws *f*, and thimbles *g*, for connecting the pivoted bar D and rod K and rendering them adjustable, substantially as and for the purpose specified.

4. In a horse-clipping machine, a shaft for 70 connecting the cutter with the main driving-wheel, said shaft consisting of the tubular rod K, adjustable rod M, flexible shaft N, rod O, tube P, rods Q S, and flexible shafts R L W, constructed, combined, and arranged to operate substantially as set forth.

5. In a horse-clipping machine, the rod K, 75 connected to the shaft *z* by means of the flexible shaft L, in combination with means, substantially as described, for rendering said rod vertically adjustable and counterbalancing the same, substantially as set forth.

ROBERT K. CARPENTER.
